UNITED STATES PATENT OFFICE

EUGENE HULACK AND JOHN W. NISSROD, OF JACKSONVILLE, FLORIDA, ASSIGNEES OF ONE-SIXTH TO H. E. COCHRAN AND ONE-SIXTH TO GEORGE L. RUTHERFORD, BOTH OF JACKSONVILLE, FLORIDA

ATTACHMENT FOR ELECTRIC DRILLS

Application filed April 25, 1930. Serial No. 447,298.

This invention relates to an attachment for electric drills and has for its primary object to provide, in a manner as hereinafter set forth, an attachment of such class by means of which an electric hand drill may be utilized for operating a saw blade, file, or other reciprocating tool.

A further object of the invention is to provide an attachment for the purpose aforementioned which includes a travelling carriage for adjustably supporting the drill, and which further includes a cam element for connection with the drill chuck to reciprocate a saw blade or the like, the adjustable support for the drill permitting the saw blade to be presented to the work with the drill disposed at various angles of inclination with respect to the travelling carriage.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:—

Figure 1 is a side elevation of an electric hand drill showing an embodiment of our invention associated therewith.

Figure 2 is a front elevation thereof.

Figure 3 is a section taken on the line 3—3 of Figure 1.

Figure 4 is a section taken on the line 4—4 of Figure 3.

Figure 5 is a section taken on the line 5—5 of Figure 3.

Figure 6 is a transverse section taken at a point indicated by the line 6—6 of Figure 1.

Figure 7 is a section taken at a point indicated by the line 7—7 of Figure 4.

Figure 8 is a plan of the clamp for the motor housing of the drill.

Figure 9 is an elevation of a combined support and guide secured to the shaft housing of the drill.

Figure 10 is an elevation of a slide carried by the element shown in Figure 9. 55

Figure 11 is a section taken at a point indicated by the line 11—11 of Figure 4.

Referring to the drawings in detail, the numeral indicates generally an electric hand drill provided with the usual chuck 2 for connection with a drill bit, not shown. The attachment consists of a travelling carriage 3 which is in the form of an elongated plate having marginal portions thereof bent in a manner to provide channels 4 in the lower face of the carriage adjacent the side edges thereof. Disposed within the channels 4 are a plurality of rollers 5 which are adapted to have rolling contact with the work, and which are rotatably supported within the channels by means of suitable shafts 6 extending through the side walls of the channels. At the forward end thereof of the carriage is provided with a recess 7 which is disposed between the channels 4 and which tapers in a rearward direction. Extending around the wall of the recess 7 is an upstanding flange 8. 70 75

Rearwardly of the recess 7, the carriage is formed with a transversely extending, vertically disposed plate 9 which is formed with an upwardly arched central portion 10. Pivotally connected to the rear face of the plate 9 by means of an adjustable bolt 11 is a supporting member 12 which is formed on its forward face with a shoulder 13 for engagement with the upper face of the central portion 10 of the plate 9. The supporting member 12 terminates at its upper end in an enlarged head 14 which is apertured transversely of the carriage for the reception therethrough of a pin 15 for pivotally connecting with the supporting member 12 a combined support and guide element indicated generally at 16. 80 85 90

The element 16 includes a clamp 17 for embracing the shaft housing 18 of the drill, the clamp merging in a plate 19 which extends in parallel relation to the housing 18 and depends therebelow. The plate 19 is 95 100

formed throughout a portion of its length with a pair of strengthening flanges 20. Formed integrally with the plate 19, in spaced relation to the lower end thereof, is a right angularly disposed supporting member 21 which is provided with spaced depending webs 22 also formed integrally with the plate. The head 14 of the supporting member 12 extends between the webs 22 and the latter are apertured for the reception of the pin 15 therethrough. The supporting member 21 is recessed in its upper face for the reception of a bearing assembly 22 carried by a stud 24 projecting from the lower end of a cam roller 25, the upper end of which is provided with a shank 26 for engagement by the chuck 2 of the drill.

Secured to the motor housing 27 of the drill is a clamp indicated generally at 28 and including a pair of oppositely disposed arcuate portions 29 embracing the housing 27. At the forward side of the housing 27, the arcuate portions 29 terminate in lugs 30 arranged in parallel relation and adapted to receive therethrough a bolt 31 which is provided with a wing nut 32. At the rearward side of the housing 27, the arcuate portions 29 merge into arcuate extensions 33 which are maintained in spaced relation by a suitable holdfast device 34 located adjacent the arcuate portions 29. Projecting between lower end portions of the extensions 33 is the upper end of an arcuate bracket 35, the lower end of which is pivotally connected to a lug 36 projecting upwardly from the carriage 3. The bracket 35 is pivotally connected to the lug 36 by means of a suitable bolt 37 which extends longitudinally of the carriage. The bracket 35 is formed with an elongated slot 38 through which a bolt 39 extends. The bolt 39 further extends through openings provided adjacent the lower ends of the extensions 33 and is provided with a wing nut 40.

45 The plate 19 of the support and guide element 16 is formed in its forward face with a dove-tailed groove 41 within which is disposed a slide 42. The slide 42 is provided on its forward face with a pair of spaced 50 ribs 43 which are formed with apertures for the extension therethrough of bolts 44. The ribs 43 are adapted to receive therebetween the base portion of a reciprocating tool, such as a saw blade 45, the tool being fixedly 55 connected with the slide by means of the bolts 44. Projecting from the rear face of the slide 42, adjacent the upper end of the latter, is a stud 46 which is provided with a roller 47 extending within and engaging 60 the side walls of a diagonally disposed groove 48 formed in the peripheral face of the cam roller 25. The stud 46 extends loosely through a slot 49 formed in the plate 19.

65 In the operation of the attachment, the

cam roller 25 is rotated by the chuck 2, and owing to the engagement of the roller 47 with the side walls of the groove 48, the saw blade 45 is reciprocated during each revolution of the cam roller. As the blade 45 cuts through the work, as indicated at 50, the carriage 3 is moved in the direction of the cut. By loosening the wing nut 40, the drill, together with the support and guide 16 may be swung about the pivot 15 as indicated in Figure 1 by dotted lines. In the dotted line showing in Figure 1, the tool 45 is shown reversed with respect to the slide 42 whereby the teeth of the tool are disposed on the forward face thereof. By loosening 70 the bolts 11 and 37, the entire attachment with the exception of the carriage 3 may be swung sidewise as indicated by dotted lines in Figure 2. In order that the drill may be accurately positioned at a lateral 75 inclination, the rear face of the central portion 10 of the plate 9 is calibrated as indicated at 51. The supporting member 12 is provided with a peep hole 52 through which the calibrations 51 are visible. In order that the attachment may be more conveniently 80 handled, an auxiliary handle member 53 is provided, such handle member being secured in position by the bolt 37. In order to hold the carriage 3 level when the drill is tilted 85 sidewise, a removable counter weight 54 may be seated on the carriage as indicated in Figures 3 and 7.

It is thought that the many advantages 90 of an attachment in accordance with this invention will be readily apparent, and although the preferred embodiment of the invention is as illustrated and described, it is to be understood that changes in the details 95 of construction may be resorted to, so long as such changes fall within the scope of the invention as defined in the appended claims.

What we claim is:

1. In an attachment for connection with the rotatable chuck of an electric hand drill, 100 a cam roller having a shank for engagement by the chuck, said cam roller having its peripheral face formed with a diagonally disposed groove, a guide element adjacent the cam roller, a tool connecting element 110 slidably mounted in the guide element, a roller carried by the tool connecting element and extending into said groove, a travelling carriage for engagement with an object to be operated upon, a vertically disposed plate 115 extending transversely of the carriage; a supporting member having its lower end pivotally connected with said plate to swing on an axis longitudinally of the carriage, said guide element having a projecting portion 120 pivotally connected with the upper end of said supporting member to swing on an axis disposed transversely of the carriage, and adjustable means for preventing movement of the guide element relative to said 125 130

supporting member, said adjustable means including a clamp secured to the drill, an arcuate extension formed on the clamp, an arcuate bracket having its lower end pivotally connected to the carriage to swing on an axis longitudinally of the carriage, said bracket being formed with an elongated slot and having an upper end portion thereof disposed in overlapping relation to said extension, and a bolt carried by said extension and extending through said elongated slot.

2. In an attachment for connection with the rotatable chuck of an electric hand drill, a cam roller having a shank for engagement by the chuck, said cam roller having its peripheral face formed with a diagonally disposed groove, a guide element adjacent the cam roller, a tool connecting element slidably mounted in the guide element, a roller carried by the tool connecting element and extending into said groove, a travelling carriage for engagement with an object to be operated upon, a vertically disposed plate extending transversely of the carriage, said plate having an arched central portion, a supporting member pivotally connected to said plate to swing on an axis extending longitudinally of the carriage, said supporting member having a shoulder riding on the upper face of said arched central portion, said guide element having a projection pivotally connected with said supporting member to swing on an axis transversely of the carriage, and means for preventing swinging movement of the guide element and supporting member with respect to the carriage.

3. In an attachment for connection with the rotatable chuck of an electric hand drill, a cam roller having a shank for engagement by the chuck, said cam roller having its peripheral face formed with a diagonally disposed groove, a guide element adjacent the cam roller, a tool connecting element slidably mounted in the guide element, a roller carried by the tool connecting element and extending into said groove, a travelling carriage for engagement with an object to be operated upon, a vertically disposed plate extending transversely of the carriage, said plate having an arched central portion, a supporting member pivotally connected to said plate to swing on an axis extending longitudinally of the carriage, said supporting member having a shoulder riding on the upper face of said arched central portion, said guide element having a projection pivotally connected with said supporting member to swing on an axis transversely of the carriage, and means for preventing swinging movement of the guide element and supporting member with respect to the carriage, said arched central portion of the transversely extending plate having a calibrated face, said supporting member being pro-

vided with a peep hole through which said calibrated face is visible.

4. In an attachment for an electric drill, a travelling carriage for adjustably supporting the drill, said carriage being in the form of an elongated plate having marginal portions thereof bent to provide the lower face of the plate with a pair of spaced channels, a plurality of rollers rotatably mounted within the channels and depending below the walls thereof, an apertured lug projecting upwardly from the plate, and a vertically disposed plate extending transversely of the carriage in spaced relation to said lug.

5. In an attachment for an electric drill, a travelling carriage for adjustably supporting the drill, said carriage being in the form of an elongated plate having marginal portions thereof bent to provide the lower face of the plate with a pair of spaced channels, a plurality of rollers rotatably mounted within the channels and depending below the walls thereof, an apertured lug projecting upwardly from the plate, and a vertically disposed plate extending transversely of the carriage in spaced relation to said lug, said vertically disposed plate having an upwardly arched central portion provided with a calibrated face.

6. In an attachment for an electric drill, a combined guide and supporting element, said element including a clamp for encircling the drill, an elongated plate formed integrally with the clamp, a supporting member projecting from the plate at a right angle thereto, and a pair of apertured, spaced webs depending from the supporting member.

7. In an attachment for an electric drill, a combined guide and supporting element, said element including a clamp for encircling the drill, an elongated plate formed integrally with the clamp, a supporting member projecting from the plate at a right angle thereto, and a pair of apertured, spaced webs depending from the supporting member, said elongated plate being formed with an elongated slot and further being formed in its forward face with a dovetailed groove.

In testimony whereof, we affix our signatures hereto.

JOHN W. NISSROD.
EUGENE HULACK.
